BOILER BASE

Marvin E. King, Cambra, Pa.

Application March 4, 1952, Serial No. 274,708

9 Claims. (Cl. 110—86)

My invention relates to improvements in furnaces and has particular reference to a furnace base unit which may be used in connection with both square or round boilers of various sizes.

One of the primary objects of the invention is to provide a base unit for furnaces having removable and interchangeable side portions one of which may carry for instance an ash pit door while another one may be provided with supporting means for a stoker unit or gun-type oil burner.

The invention also resides in novel means for supporting the upper sections of a boiler whether of the square or round type.

The invention also contemplates a unit as characterized which is simple and inexpensive in construction, easy to assemble, is highly efficient in practical use and the parts of which when assembled providing an enclosed ash pit for accommodating an ash-receiving tub, there being a large door-controlled opening through which the tub may be inserted or removed.

Various other objects and advantages of the invention will be understood and appreciated by those skilled in the art upon reference to the accompanying drawings which illustrate a now preferred example of the invention. It is to be understood, however, that my inventive concept is susceptible of other mechanical expressions within the spirit and scope of the subject matter claimed hereinafter.

In the drawings, wherein the same reference characters have been used to designate the same parts throughout the several views—

Fig. 1 is a perspective view illustrating my base unit in connection with a square boiler and a hopper-type stoker;

Fig. 2 is another perspective view illustrating the base unit in connection with a so-called "round" type boiler and in connection with a bin-fed stoker;

Fig. 3 is a perspective illustration of the removable base wall with which the stoker unit of Fig. 2 is associated;

Fig. 4 is an exploded perspective view of the base unit as employed for either square or round boilers;

Fig. 5 is a vertical sectional view taken through the assembled base unit of Fig. 4, the lower end of an associated boiler unit being shown;

Fig. 6 is a top plan view of the base as shown in Figs. 3 and 4;

Fig. 7 is a side elevational view of the stoker wall side of the base;

Fig. 8 is another side elevational view but illustrating the ash-pit door carrying wall; and

Fig. 9 is another side elevational view illustrating one of the plain interchangeable walls.

Referring specifically to the drawings by reference characters, my novel base is generally designated by reference character 15 and in Fig. 1 is shown supporting the upper section of a square-type boiler 16 having fire-box door 16a and a flue cleanout door 16b.

Associated with the base and boiler unit of Fig. 1 is a

2

hopper-type stoker unit designated by numeral 17 and which includes the hopper 18 which is supported by legs 19 and discharges into the vertical box-form conduit 20.

It is to be understood that the stoker unit 17 is or may be of any standard construction and per se forms no part of my invention. It may be noted, however, that the stoker assembly 17 of Fig. 1 has the coal supply conduit 21 which communicates with the hopper-conduit 20 and has the driven conveyor (not shown) therein for supplying the coal to the burner such as is shown as 32 in Fig. 3. Numeral 22 indicates an electric motor having the belt driven connection with the pulley 23 of a blower 23b which supplies air into the furnace base through the pipe 21a. In the particular stoker of Fig. 1 the screw-conveyor (not shown) of the conduit 21 will be chain driven in well known manner from the blower unit 23b as indicated generally by reference character 23a.

Referring to Fig. 2 the round-type boiler unit is indicated by numeral 24 and has the fire-box door 25 and the rearwardly extended flue pipe 26. The stoker unit of Fig. 2 has the screw conveyor-incorporating pipe 27 leading from a coal bin (not shown) which pipe 27 discharges into a subjacent right-angularly disposed conveyor-incorporating pipe 28 which is shown in Fig. 3 as carrying at its inner end and within the base section the conventional fire-pot 32, to which incidental reference has been made in connection with the description of Fig. 1. The stoker unit of Figs. 2 and 3 is standard or may be and no novelty is claimed for same. The stoker unit of Figs. 2 and 3 has the drive-motor 31 for the pulley 29b of the blower 29 which discharges air into the furnace base through the manifold 30. The conveyor pipe 28 has an attaching flange 28a for attachment to one of the base sides as indicated in Fig. 3. The conveyor of the conduit 28 is driven from the blower 29 by a chain or the equivalent 29a and the conveyor of the pipe or conduit 27 is driven from the earlier-mentioned conveyor by means of gearing 28b all of which is standard.

Coming now to the novel base member 15 which is the subject of my invention, Figs. 4 and 5 show the same as comprising the bottom plate 33 from the corners of which rise the angle-form posts 34 whose upper ends are connected by angle-bars 35. The horizontal flanges 35a of the angle-bars may provide the seating support for the boiler section or unit 16 of Fig. 1 when the cross-sectional dimensions of same substantially conform to those of the base 15 or, in other words, when the square boiler 16 can be seated within the space defined by and immediately adjacent the up-standing flanges 35b of the angle-bars 35 as indicated in Fig. 5. When, however, the dimensions of the square boiler unit 16 are materially less than the cross-sectional dimensions of the base 15, or when a round boiler such as 24 is to be installed, the plate 36 of Fig. 4 will be disposed upon the angle-bar flanges 35a as is shown in Fig. 5 and the boiler unit such as 16 or 24 supported upon the plate 36 about the central hole 37 therein. Plate 36 will preferably be welded or otherwise fastened to the horizontal angle bar flanges 35a.

The disclosures of Figs. 4, 5 and 6 indicate how the horizontal angle-bar flanges 35a of the base support the boiler sustaining plate 36 which acts with such flanges 35a in the support of either a round or square boiler such as 16 and 24.

Referring to Fig. 4 and also to Figs. 5—9, inclusive, it will be noted that the side closure plates 42, 43, 44, and 45 are interchangeable and that each has marginal holes 50 which are adapted to register with holes 51 of the posts 34 to admit of such plates being bolted in place as indicated at 52 in Figs. 5—9, inclusive. When the closure plates are assembled an enclosed ash pit is provided for receiving the tub 53 which is removable

through the ash door controlled opening. Dust incident to ash removal is thus eliminated.

The plate 42 is shown as having the usual ash-pit door 46 which is hinged to the plate as indicated at 46a, the free end of the door having the usual latch or keeper element 47.

The plate 43 is the one which carries the stoker unit, or rather through which the blower pipe and coal supply pipe extend. Thus, the closure plate 43 has a hole 48 for the coal supply conduit 28 of Fig. 3 or the coal supply conduit 21 of Fig. 1 and the air admission opening 49 for communication with the blower conduit or manifold 30 of Fig. 2 or 21a of Fig. 1. The other two plates 44 and 45 complete the enclosure of the base.

It is to be noted that when the walls 42, 43, 44 and 45 are in place as shown in Figs. 5-9, inclusive, the upper ends of same overlie the lower portions of the angle-bars 35 so as to reinforce the furnace seat. The interchangeability of the walls of the base 15 is important because it admits of the stoker unit and ash door being located at selected ones of the four base sides so that available space in the region of the furnace can be used to the best advantage. Thus, employment of my base unit 15 makes it immaterial whether the coal bin or the best location for the stoker hopper (Fig. 1) is at any one of the three sides. I say any one of three sides although it is really four because the unit 15 will usually be set close to the chimney wall so that a short flue pipe can be employed to establish connection between the boiler and the chimney flue.

Although I have mentioned stokers as the heating unit, it will be understood that oil burner or gas burner units may be substituted—the principle involved being the same.

Having thus described my invention, what I claim is:

1. A firebox-providing boiler base section providing a boiler-supporting seat adjacent its top and having openings at a plurality of lateral sides, interchangeable closure plates for said openings, means detachably securing said closure plates to said base over said openings, a door carried by one of said closure plates and affording access to the firebox interior, and a burner unit for disposition within said base through a selected one of said openings, said burner unit incorporating one of said plates as a closure for said openings and positionable over a selected one of the latter when the burner is in operative position within said base.

2. A firebox providing base section for boilers which are either generally rectangular or generally round in cross section, and base section comprising a frame providing openings in at least three of its lateral sides, said frame being shaped to generally conform to the cross section of the bottom of a predetermined large size of one of said types of boilers, said base-providing frame having an endless upstanding boiler side-receiving flange and a subjacent inwardly extending boiler-supporting flange member at opposed sides, a boiler supporting plate positionable on said boiler supporting flange members and having a central opening of a size and shape generally conforming to the internal cross section of the boiler to be supported thereon, interchangeable closure plates for said base openings, means detachably securing said closure plates to said base frame over said openings, and a burner unit carried by one of said closure plates and which is adapted to be projected through any one of said openings into said base section.

3. A firebox-providing base section for boilers which are either generally rectangular or generally round in cross section, said base section comprising a frame providing openings in at least three of its lateral sides, said frame being shaped to generally conform to the cross section of a predetermined large size of one of said types of boiler, said base-providing frame having an inwardly extending boiler-supporting flange member adjacent its top at opposed sides, a boiler supporting plate position-

able on said flange members and having a central opening of a size and shape generally conforming to the internal cross section of the boiler to be supported thereon, interchangeable closure plates for said base openings, means detachably securing said closure plates to said base frame over said openings, one of said closure plates having mounting means for a burner unit which is adapted to be projected from said plate through any one of said base section openings which is closed by said mounting means incorporating plate and into said base section provided fire-box, and an ash-pit door carried by another of said closure plates.

4. A firebox-providing base section for boilers which are either generally rectangular or generally round in cross section, said base section comprising a frame providing openings in at least three of its lateral sides, said frame being cross-sectionally shaped to generally conform to the cross section of a predetermined large size of one of said types of boilers, said base-providing frame having an inwardly extending boiler-supporting flange member adjacent its top at opposed sides, interchangeable closure plates for said base openings, means detachably securing said closure plates to said base frame over said openings, one of said closure plates having mounting means for a burner unit which is adapted to be projected from said plate through any selected one of said openings into said base section when said plate is in opening closing position, and said frame-provided base comprising a square bottom plate, angle iron posts rising from the corners of said bottom plate, angle iron bars connecting the upper ends of said posts and cooperating with the latter to provide said base openings, said angle iron bars having horizontally disposed flanges constituting said boiler-supporting flange members and also providing outwardly disposed upwardly extending flanges extending above the plane of said boiler-supporting flange.

5. A fire box-providing boiler base section providing a boiler load-supporting seat adjacent its top and having openings at each of a plurality of lateral sides, interchangeable closure plates for said openings, each plate selectively positionable to close any one of said openings, means detachably securing said closure plates to said base over said openings, a burner unit-incorporating assembly and providing a burner unit adjacent one end and a fuel supply means as a support therefor, said assembly incorporating one of said plates as a combined burner portion shield and base opening closure, said plate and supply means mutually supported by one another and the supply means extending through said plate, and said burner unit being projectable through any one of said openings to be wholly within said base section.

6. The structure set forth in claim 5, and said base section comprising a skeleton frame including a bottom member, laterally spaced upstanding posts carried thereby, horizontal angle bars connecting said posts adjacent their upper ends, said angle bars providing horizontal inwardly extending boiler load-supporting flanges and upstanding boiler confining flanges, and said interchangeable closure plates having their ends detachably secured to said posts and closing the respective angle iron and bottom member bounded openings therebetween.

7. The structure set forth in claim 5, and said base section comprising a skeleton frame including a bottom member, laterally spaced upstanding posts carried thereby, horizontal angle bars connecting said posts adjacent their upper ends, said angle bars providing horizontal inwardly extending boiler load-supporting flanges and upstanding boiler confining flanges, said interchangeable closure plates having their ends detachably secured to said posts and closing the respective angle iron and bottom member bounded openings therebetween, and the upper portions of said plates overlying and reinforcing said vertical boiler-confining angle iron flanges.

8. The structure set forth in claim 5, and said base section comprising a skeleton frame including a bottom

member, laterally spaced upstanding posts carried thereby, horizontal angle bars connecting said posts adjacent their upper ends, said angle bars providing horizontal inwardly extending boiler loading-supporting flanges and upstanding boiler confining flanges, said interchangeable closure plates having their ends detachably secured to said posts and closing the respective angle iron and bottom member bounded openings therebetween, and a boiler supporting plate positionable on said horizontal flanges and having a central opening of a size and shape generally conforming to the internal cross-section of the boiler to be supported thereon.

9. The structure set forth in claim 5, and said base section comprising a skeleton frame including a bottom member, laterally spaced upstanding posts carried thereby, horizontal angle bars connecting said posts adjacent their upper ends, said angle bars providing horizontal inwardly extending boiler load-supporting flanges and upstanding boiler confining flanges, said interchangeable closure plates having their ends detachably secured to said posts and closing the respective angle iron and bottom member bounded openings therebetween, the

upper portions of said plates overlying and reinforcing said vertical boiler-confining angle iron flanges, and a boiler-supporting plate positionable on said horizontal flanges and having a central opening of a size and shape generally conforming to the internal cross-section of the boiler to be supported thereon.
